UNITED STATES PATENT OFFICE.

GUSTAVUS A. MONTGOMERY, OF DALLAS, TEXAS, ASSIGNOR OF ONE-HALF TO THE
GUIBERSON CORPORATION, OF DALLAS, TEXAS, A CORPORATION OF DELAWARE.

BIT-HOLDING TOOL.

1,407,292.

Specification of Letters Patent. Patented Feb. 21, 1922.

Application filed August 2, 1920. Serial No. 400,696.

To all whom it may concern:

Be it known that I, GUSTAVUS A. MONTGOMERY, a citizen of the Republic of Finland, residing at Dallas, in the county of Dallas and State of Texas, have invented certain new and useful Improvements in Bit-Holding Tools, of which the following is a specification.

This invention relates to new and useful improvements in bit holding tools.

In the redressing or shaping of well drilling bits it is customary to grasp the same in a pair of tongs and dress the cutting edge of the bit over an ordinary blacksmith's anvil. It is generally necessary to shift the tongs and the latter do not always hold the bit in a satisfactory manner. The purpose of my invention is to provide a tool on which the well bit may be securely fastened and whereby it may be held in a convenient and satisfactory manner for dressing or otherwise treating the well bit. A particular feature is to provide a tool with means for receiving the shank of the bit and holding the bit securely and against movement independent of the tool. Another feature of the invention is to provide means for fastening a pair of bits on the tool in substantially the same position and relation they would occupy when being used in the well, thus permitting the cutting diameter to be gauged and other adjustments made without inserting the bit in the reamer body or cutter head, which would require considerable time and labor.

In carrying out the invention I provide an elongated handle member with a head or enlarged portion at one end. On one of the flat sides of this head or portion I provide a socket or counter-sunk seat which is shaped to snugly receive the shank of the well bit so that when said shank is in said socket, the bit cannot move laterally of the head. A fastening device is arranged to pass through the pivot hole of the shank of the bit and also through the bottom of the socket and includes means for effecting a quick and efficient fastening operation. By duplicating the socket on the other side of the head and employing an elongated fastening device, two bits may be fastened to the tool in the same position they would occupy in an underreamer body or other tool. With the bits thus fastened their cutting edges may be gauged and their diameter determined the

same as if they had been inserted in the underreamer body which would require a considerable length of time. It will be seen that with a bit or bits fastened on a tool of this nature there is no danger of the workman dropping the bit from the tool and he may lay the same down and pick it up again without the bit being disengaged from the tool. The bit will be securely held and a dressing or reshaping operation can be more satisfactorily and easily carried out.

The invention will be more readily understood from a reading of the following specifications and by reference to the accompanying drawings, in which an example of the invention is shown, and wherein:

Fig. 1 is a side elevation of a tool constructed in accordance with my invention and showing an underreamer bit fastened on said tool.

Fig. 2 is an elevation at right angles to Fig. 1, a portion of the head being illustrated in section.

Fig. 3 is a cross-sectional detail on the line 3—3 of Fig. 1.

Fig. 4 is an elevation of a modified form for holding two bits, a portion being illustrated in section, and

Fig. 5 is a cross-sectional detail on the line 5—5 of Fig. 4, the bits being omitted.

In the drawings the numeral 10 designates an elongated handle member which may be of any desired length and of any shape, and is preferably made of metal. At one end the handle member has a flat head or enlarged portion 11. The width of this portion as well as the length will depend upon the size of the bit which is to be handled. In one side or face of the head a counter-sunk socket 12 is provided. I have shown this socket with one continuous inclined wall 13 at one side and an angular wall 14 at the other side, these walls being shaped to snugly receive the edges of the shank A of an underreamer bit B. The bit illustrated has a shoulder C and the end of the head is abutted by this shoulder. It will be seen that the shank A, fits snugly in the socket.

The shank A of the bit has a transverse opening D which receives the pivot bolt (not shown) of the reamer, and on which the bit is carried. A hole 15 is made through the head in the bottom of the socket 12 so as to register with the opening D when

the shank A is inserted in the socket. A bolt 16 is passed through the hole 15 and the opening D and receives a nut 17 which is provided with a handle 18 having an upturned end or tip 19. The nut engages the outer side of the shank A and forces said shank into the socket. A handle 18 affords an ample leverage whereby the nut may be quickly rotated and the parts tightly drawn together. The upturned end 19 provides means whereby the handle may be more efficiently held or may be given a light blow either to tighten or loosen the nut as will be obvious. With the shank of the bit securely fastened in the tool it will be seen that the workman may freely handle the bit and will not have to pay any attention to his hold on the same like he would with a pair of tongs. He may give his entire time and attention to the dressing of the cutting edge and may lay the bit down and pick it up again without disconnecting the parts. When the bit is inserted in the fire for heating it is not detached from the tool and, therefore, may be readily withdrawn and cannot be lost.

In Figs. 4 and 5 I have shown a slightly modified form in which a second socket 12' is formed on the opposite side of the head 11, for receiving the shank A' of a bit B'. A bolt 16' is passed through the hole D' of the shank A', the hole 15 of the head and the hole D of the shank A. A nut 17' is mounted on the bolt and is provided with

a handle 18' and an upturned end 19'. By manipulating these parts the shanks of the bits are tightly drawn into the sockets and the bits held in the same relation in which they would be held in a reamer body, thus permitting the workman to gauge the radius and diameter and otherwise test out the same as will be obvious. It is to be understood that the tool may be made with one socket or with both sockets, and where made with two sockets, one of these may be used for dressing a single bit if desired.

What I claim, is:

A device for holding and manipulating a plurality of well bits in dressing the same, comprising a substantially straight elongated handle provided at its forward end with a substantially flat head extending forwardly of the handle, said head being provided upon its opposite faces with sockets, each socket having its outer side and forward end open, said head having a transverse opening extending through the sockets, said sockets being adapted to receive the shanks of a pair of drill bits, whereby the bits are held assembled in the position they occupy when in use, said shanks having transverse openings, and a bolt passing through the transverse openings of the shanks and the head, and a nut carried by the bolt and provided with a radial handle whereby the nut may be readily turned.

In testimony whereof I affix my signature.
GUSTAVUS A. MONTGOMERY.
